Attorneys.

UNITED STATES PATENT OFFICE.

THOMAS R. KINNUCAN, OF CHICAGO, ILLINOIS.

FENCEPOST.

Application filed January 22, 1923. Serial No. 614,277.

To all whom it may concern:

Be it known that I, THOMAS R. KINNUCAN, a citizen of the United States, residing at Chicago, in the county of Cook 5 and State of Illinois, have invented new and useful Improvements in Fenceposts, of which the following is a specification.

My invention relates to fence posts and more particularly to a fence post which is especially adapted for use in connection with wire fences, the invention having for its primary object the provision of a fence post which when used in conjunction with a wire fence may be so positioned that it 10 will maintain the wire strands in alinement and at the same time resist disengagement of the strands therefrom by reason of lateral pressure thereagainst, thus making the fence very stable and overcoming the difficulty with most wire fences, viz., disengagement of the wires from the posts and the resultant sagging thereof.

Another important object of the invention is to provide a post of this kind which is 15 very strong and durable, inexpensive of manufacture, and which may be easily driven into the ground and effectually maintained therein.

With the above and other objects in view, 20 as will become more apparent as the description proceeds, the invention comprises certain novel features of construction which will be hereinafter described and claimed, and in order that the same may be better understood reference is had to the accompanying drawings forming a part of this specification.

In the drawings,

Figure 1 is an elevation of my post; Fig. 20 40 a top plan view thereof showing wires attached, and Fig. 3 a top plan view of a portion of a fence showing the application of the invention.

Referring now specifically to the drawing 45 wherein like reference characters designate like parts throughout the several views, numeral 5 denotes a fence post constructed in accordance with my invention having a base or earth engaging portion 6, the lower extremity of which is preferably pointed as shown at 7, and the longitudinal sides of the earth engaging portion are provided with surface ribs 8 to resist withdrawal of the earth engaging portion when it has been 50 driven into the ground.

It will be noted that the wire carrying

portion of the post above the ground, denoted at 9, is laterally offset from the earth engaging portion 6 as shown at 10, the purpose of which will be presently described. 60 The upright wire carrying portion 9 and also the offset portion are both provided with annular enlargements 11 for engagement with the loop 12 of the wire strand 13 thus maintaining the wire strand in 65 spaced relation and preventing spreading thereof. By providing the laterally offset portion 10 with annular enlargements 11, it will be evident that the post will be especially fitted for use in connection with fencing for enclosing animals of the burrowing or digging variety and will render their escape by digging under the bottommost wire very difficult.

The post is preferably constructed of 75 metal, but may be formed with almost equal facility of wood. In driving the post into the ground it will be seen that the lateral offset portion 10 forms a striking surface for the mallet or other instrument used in 80 positioning the post in the ground, and thus it is unnecessary to dig a hole first as is the usual custom when posts of considerable height are used.

A further object of the formation of the 85 post with its upright portion offset from the ground engaging portion, is to permit the construction of a fence whereby the posts may be positioned alternately along the line of the fence so that they may face 90 the wire from opposite sides. It will be evident that this lends stability to the fence, as strains suffered by the wires are resisted from either side, helping to keep the wire well in alinement, and at the same time preventing disengagement of the wire therefrom.

In accordance with the patent statutes, I have described and illustrated the preferred embodiment of this invention, but it 100 will be understood that various slight changes and modifications may be made therein within the spirit and scope of the following claims.

Having thus described my invention, what 105 I claim as new and desire to secure by Letters Patent is:

1. A fence post comprising a ground engaging portion, a lateral offset at the top of said ground engaging portion, an upright wire carrying portion carried by said lateral offset, and annular enlargements car-

ried by said offset and upright portions for abutting and retaining the wire strands of the fence in spaced relation to each other.

2. A fence post comprising a ground engaging portion, a lateral offset at the top of said ground engaging portion, an upright wire carrying portion carried by said lateral offset, and annular enlargements carried by said offset and upright portions for

abutting and retaining the wire strands of the fence in spaced relation to each other, and surface ribs carried by said ground engaging portion for preventing withdrawal of the same from the ground.

In testimony whereof I affix my signature.

THOMAS R. KINNUCAN.
